UNITED STATES PATENT OFFICE.

CHARLES W. COVELL, OF WILKINSBURG, PENNSYLVANIA, ASSIGNOR TO WESTINGHOUSE ELECTRIC AND MANUFACTURING COMPANY, A CORPORATION OF PENNSYLVANIA.

INSULATING-SUPPORT.

1,244,473.

Specification of Letters Patent. Patented Oct. 30, 1917.

Application filed September 25, 1914. Serial No. 863,502.

To all whom it may concern:

Be it known that I, CHARLES W. COVELL, a citizen of the United States, and a resident of Wilkinsburg, in the county of Allegheny and State of Pennsylvania, have invented a new and useful Improvement in Insulating-Supports, of which the following is a specification.

My invention relates to insulating supports for electrical devices, and it has special reference to supports which may be utilized upon current-limiting reactance coils of various diameters.

Inasmuch as the manufacturer is required to furnish a great number of reactance coils of different sizes and capacities for a variety of operating and service conditions, it has been substantially impossible to design suitable reactance coils which all conform to standard and common dimensions. By reason of this, it has been necessary heretofore to provide new insulating supports for each differently sized coil, thereby greatly increasing the number of manufacturing parts required and the attendant first cost of the coils.

One object of my invention is to provide an insulating support that may be employed in connection with reactance coils having widely differing diameters and which conform, in general, to a certain general design.

Another object of my invention is to provide an insulating support which will be mechanically rigid and easy to attach to a reactance coil.

For a more complete understanding of my invention, reference may be had to the following description and the accompanying drawing in which Figure 1 is a view, partially in elevation and partially in section, of an insulating support built in accordance with my invention; Fig. 2 is a top plan view of the support shown in Fig. 1, and Fig. 3 is a partial plan view, looking upward, of the bottom of a reactance coil equipped with one of my insulating supports.

Referring to Figs. 1 and 2, I provide a top plate 1 having two oppositely projecting arms 2 and 3 which preferably lie in the same plane and are angularly displaced an angle of less than 180 degrees from each other. A central recess 4 is formed intermediate the arms 2 and 3 in which is secured an upper end portion 6 of a built-up in-

sulator 5. The upper portion 6 of the insulator that is located in the recess 4 is provided with a corrugation 7 which is engaged by cement 8 poured into the recess 4 in order to rigidly hold the plate 1 upon the insulator. A cast iron foot 9 has an upper end 10 that projects into a recess 11 formed in the insulator 5. The foot 9 is held rigidly in fixed relation to the insulator 5 by means of cement 8. In each of the arms 2 and 3 of the plate 1 is formed an elongated slot 12 which is disposed midway between the side edges and extends lengthwise of the arm.

By referring to Fig. 3, it will be apparent that my insulating support, by reason of the angularly disposed arms 2 and 3 and the elongated slots 12 formed therein, may be applied to reactance coils of many different sizes. A common form of reactance coil is shown in which conductors 13 are spaced from one another and rigidly held in fixed relationship by means of a series of built-up columns comprising insulating and radially extending cleats 14. Each of the insulating supports is secured to two bottom cleats 14, substantially as shown, the central portion of the support being disposed adjacent to an intermediate cleat. Bolts 15 project through the slots 12 in the arms 2 and 3, and are provided with nuts 16 to secure the support to the reactance coil.

Because of the elongated slots 12 and their disposition in the arms 2 and 3, my insulating supports may be expeditiously applied to a large variety of reactance coils having different diameters. For instance, the radial cleats 14 may be spaced greater distances from one another than those shown in Fig. 3, but, by reason of the elongated slots 12, the bolts 15 may engage the cleats 14 and thereby firmly hold my insulating support in position. It will be understood that more than one insulating support will be required for each reactance coil.

When it is desirable to dispose the reactance coil in a fixed position, bolts may engage recesses 17 formed in the base of the cast iron foot 9. At the same time, the coil is thoroughly insulated from the bed plate to which the foot 9 may be secured by reason of the interposition of the insulator 5 which engages the cast iron plate 1.

While I have shown and described one embodiment of my invention, it will be

understood that many modifications may be made therein without departing from the scope of the appended claims.

I claim as my invention:

5. 1. A support comprising a top plate having laterally projecting arms and an intermediate recess, said arms being provided with longitudinal slots that are spaced from each other on an arc having a finite radius 10 of curvature, an insulator having its upper end seated in said recess, and a metallic foot secured to said insulator and insulated thereby from said top plate.
15. 2. A support comprising a plate having laterally projecting arms which are provided with longitudinal slots that are spaced from each other on the same circumference having a finite radius, a recessed insulator secured at its top portion to said top plate, and a 20 metallic foot which projects into the recess formed in the insulator.
3. A support comprising a member hav-

ing laterally and oppositely projecting arms that are provided with elongated slots in their outer ends, the slots being spaced from each other on an arc having a finite radius 25 of curvature, a metallic foot, and an insulator interposed between said member and said metallic foot.

4. A support comprising a top plate having laterally extending arms that are provided with slots at their outer ends, the angle included between the center lines through the slots being less than 180°, and an insulating foot secured to the support intermediate said arms. 30

In testimony whereof, I have hereunto subscribed my name this 22 day of Sept., 1914.
